UNITED STATES PATENT OFFICE.

CHARLES JACOBS, OF CONEY ISLAND, NEW YORK.

DESIGN FOR AN AMUSEMENT BOAT.

Application filed March 9, 1928. Serial No. 25,780. Term of patent 3½ years.

To all whom it may concern:

Be it known that I, CHARLES JACOBS, a citizen of the United States, and residing in Coney Island, New York, in the county of Kings and State of New York, have invented a certain new, original, and ornamental Design for Amusement Boats, of which the following is a specification, reference being had to the accompanying drawing, forming a part thereof, and which shows in Fig. 1 a side elevation and in Fig. 2 an end elevation of an amusement boat showing my new design.

I claim:

The ornamental design for an amusement boat as shown.

CHARLES JACOBS.
